UNITED STATES PATENT OFFICE

2,600,726

UNSCRAMBLER AND SPACER

Maurice H. Behrens, Audubon, N. J.

Application July 1, 1948, Serial No. 36,403

2 Claims. (Cl. 198—30)

1

This invention relates to an apparatus designed primarily for use in food packing plants wherein canned or packaged fruits and vegetables are packed in cans, jars, bottles, etc., for shipment.

The primary object of the invention is to provide an apparatus of this character which will arrange the empty containers, so that when the empty containers are delivered to the packers, the empty containers may be conveniently filled or packed.

An important object of the invention is to provide an apparatus of this character which may be adjusted to adapt the device for use in handling containers of various sizes.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawings:

Figure 1 is a side elevational view of an unscrambler or spacer constructed in accordance with the invention.

Fig. 2 is a plan view thereof.

Fig. 3 is an end elevational view of the apparatus.

Fig. 4 is a perspective view of the bearing supporting bracket for the sprocket shaft at one end of the apparatus.

Fig. 5 is a sectional view taken on the line 5—5 of Fig. 1.

Fig. 6 is a fragmental perspective view illustrating the forward ends of the stop bars and guide fingers supported at their ends.

Fig. 7 is a perspective view illustrating a shaft and bearing supporting bracket at one end of the apparatus.

Referring to the drawings in detail, the apparatus comprises a frame embodying upper and lower spaced longitudinal bars 5 and 6 respectively, which are connected at their ends by means of the transverse bars 7 and vertical bars 8 and 9. Vertical bars 10 are disposed at one end of the frame of the apparatus and are spaced from the bars 9, providing a support for one end of an upper frame, the bars 9 and 10 being connected at their upper ends by means of the transverse bar 11 that is of a length to extend an appreciable distance beyond the vertical bar 10, where it provides a support. At opposite sides

2

of the frame of the apparatus and disposed in spaced relation with respect to the bars 9 and 10, are vertical bars 12 arranged on opposite sides of the frame, the bars 12 extending an appreciable distance above the ends of the vertical bars 9 and 10, as shown by Fig. 1 of the drawings.

In securing the bars together in the formation of the frame, the preferred manner of securing the bars together is by welding, wherein wide plates such as indicated at 13 and 14 are used at the ends of the various bars providing wide supporting surfaces to withstand severe strain. Mounted within the frame is the variable speed motor 15, the shaft of which is provided with the sprocket 16 over which the chain 17 operates, the chain 17 also operating over the sprocket 18 mounted on the shaft 19 transmitting movement to the shaft 19.

Secured to the shaft 19 is the sprocket 20 over which the chain 21 operates, which chain also operates over sprocket 22 secured to the shaft 23 of the apparatus.

The sprocket 24 is secured to one end of the shaft 23 and accommodates the chain 25 that moves over the sprocket 26 secured to one end of the shaft 27 mounted in bearings 28 secured to the upper portion of the frame of the apparatus. Secured to the shaft 27 is the horizontal conveyor roller 29 over which the conveyor 30 operates the conveyor 30 also operating over the conveyor roller 31 mounted at the opposite end of the frame of the apparatus. The upper flight of the conveyor 30 moves over the horizontal supporting surface or table 32, which is supported on the transverse bars 33 that are secured to the bars 5, the bars 33 extending transversely of the bars 5.

The upper ends of the vertical bars 12 provide supports for the spaced guide bars 34 that are arranged in pairs, as clearly shown by Fig. 1 of the drawings. The bars 12 are formed with elongated openings 35 in which the bolts 36 operate, the bolts 36 being secured in threaded openings formed in the bars 34, whereby the bars 34 may be adjusted vertically with respect to each other to adapt the device for use in sorting containers of various sizes.

At the front end of the frame of the apparatus, is the pinion 35 which is secured to the shaft 23, the pinion 35 meshing with the pinion 36 secured to the vertical shaft 37 that extends upwardly and passes through a bearing secured to bar 11 where it provides a support for the sprocket 38, which operates in a hori-

zontal plane. At the opposite side of the frame, the sprocket 39, which also operates in a horizontal plane, the sprockets 38 and 39 accommodating the chain 40 which also moves over the idle sprocket 41 mounted on the adjustable arm 42, secured to the bar 11. Extending from the chain 40 are separating plates 43 that extend laterally from the chain in predetermined spaced relation with respect to each other, the chain 40 and plates 43 moving transversely over the conveyor 30 at one end thereof, as clearly shown by Fig. 2 of the drawings.

The spaced guide bars 34 at one side of the upper surface or table of the frame, provide supports for the curved guide fingers 44 that extend forwardly and in such spaced relation with respect to the chain 40 that spaces are provided between the plates 43 and guide fingers 44 to permit but one can or container between adjacent plates 43 and fingers 44 as the chain operates and the plates 43 move. As clearly shown by Fig. 2 of the drawings the chain 40 moves between the horizontal guide bars 45 disposed at one end of the shaft, the guide bars being supported by means of the curved arms 46 and 47, the arm 47 being secured to the bar 11, while the arm 46 extends upwardly from the supporting plate 48. The plate 48 also provides a support for the bearing in which the shaft 49 of the sprocket 39, operates. Elongated openings 50 are formed in the plate 48 and accommodate the bolts 51 to permit of lateral adjustment of the plate 48 to pick up slack in the chain between the sprockets 38 and 39.

The plate 48 is also provided with a vertical arm 52 formed with openings 53 elongated vertically so that the plate 48 may be adjusted vertically to properly align the chain 40. Adjacent to the forward end of the apparatus and arranged at one side thereof, is a wide plate 54 that supports one end of the endless conveyor 55, which is so arranged that when containers are released from spaces between adjacent separating plates 43, the containers will be delivered to the endless conveyor 55 in a single row and spaced apart so that they may be readily filled or packed without removing them from the conveyor and continue on to the following operation such as juicing, capping, washing and labeling.

In mounting the conveyor 55 it is contemplated to use a pivoted bracket such as indicated at 56, the bracket supporting the conveyor roll 57, which the conveyor 55 operates. Thus it will be seen that the conveyor 55 may be adjusted to various angular positions for the convenience of the packers using the apparatus.

From the foregoing it will be seen that due to the construction shown and described, I have provided an unscrambling and spacer apparatus wherein empty containers such as cans, jars, bottles, etc., may be deposited on one end of the conveyor 30 in an upright position, the articles moving forwardly where they find their way into the spaces between adjacent plates 43. Since the plates 43 move laterally of the conveyor 30, it is obvious that they will be de-

posited on the conveyor 55 in an upright position and spaced apart where they may be conveniently filled or packed by the packer.

Having thus described the invention, what I claim is:

1. An apparatus for unscrambling and spacing containers for packing, comprising a frame, a conveyor belt operating in a horizontal plane, mounted on the frame and onto which containers to be packed are delivered in a scrambled condition, an operating chain operating directly over said conveyor belt at the discharge end thereof, and operating at right angles to the conveyor belt, said operating chain extending beyond the side edges of the conveyor belt, spaced vertical separating plates having one of their respective ends secured to the chain, extending laterally therefrom providing spaces within which the containers move, said plates providing pushers for pushing the containers laterally from the conveyor belt, and an endless horizontally movable conveyor belt operating at one side of the first mentioned conveyor belt at the discharge end thereof onto which the containers are delivered and carried from the frame, and a pair of curved spring fingers vertically spaced, extending laterally from said frame at one end thereof, against which said containers move directing said containers laterally onto said horizontally movable conveyor belt.

2. An apparatus for unscrambling and spacing containers for packing, comprising a frame, spaced vertically adjustable guide bars extending longitudinally of the frame along the side edges of the frame, a main conveyor belt operating in a horizontal plane, mounted on the frame between said guide bars at the sides of the frame and onto which containers to be packed are delivered, a separating chain disposed directly over said conveyor belt at the discharge end thereof, and operating at right angles to the main conveyor belt, said operating chain extending beyond one side edge of the main conveyor belt, spaced members on the chain between which containers positioned on the main conveyor belt are fed, curved fingers mounted adjacent to the discharge end of the main conveyor belt, and secured to the spaced guide bars, said fingers cooperating with the operating chain in directing containers laterally of the main conveyor, and an endless conveyor operating in parallel relation with the main conveyor at the discharge end of the main conveyor, onto which containers are directed by said curved fingers.

MAURICE H. BEHRENS.
